Primary Examiner — Susan Bennett Hattan*Assistant Examiner* — Marie Fast Horse(74) *Attorney, Agent, or Firm* — Feldman Gale, P.A.; Robert Weaver**CLAIM**

The ornamental design for a lighter, as shown and described.

DESCRIPTION

FIG. 1 is a front perspective view of a lighter according to the present invention in a closed position;

FIG. 2 is a front perspective view of the lighter of FIG. 1 in an open position;

FIG. 3 is a front view of the lighter of FIG. 1 in an open position;

FIG. 4 is a first side view of the lighter of FIG. 1 in an open position;

FIG. 5 is a second side view of the lighter of FIG. 1 in an open position;

FIG. 6 is a rear view of the lighter of FIG. 1 in an open position;

FIG. 7 is a top view of the lighter of FIG. 1 in an open position; and,

FIG. 8 is a bottom view of the Lighter of FIG. 1 in an open position.

Features shown in broken lines depict parts of the lighter that form no part of the claimed design.
